UNITED STATES PATENT OFFICE

2,490,910

ELECTRIC BED WARMER

John S. Latta, Sr., Cedar Falls, Iowa

Application February 20, 1947, Serial No. 729,757

2 Claims. (Cl. 219—45)

1

The present invention relates to electric heaters or warmers.

An object of the invention is the provision of a simple and compact device, utilizing for the most part existing materials, for producing a heater or warmer.

The device of the present invention includes a container and an electric light bulb, which has a wide variety of uses.

An additional advantage of the invention resides in the fact that the device is entirely safe and will not short-circuit or burn or break.

Still another object is the provision of such a heater which has an unusually long life.

Still another object of the invention is the provision of such a device which is practical and inexpensive both in initial cost and in continuing upkeep.

A still further object is the provision of such a heater which is unusually efficient. Such efficiency resides primarily in the fact that all of the heat generated is utilized.

One of the uses of the device is utilizing it as a bed warmer.

With these and other objects in view, my invention consists in the construction, arrangement and combination of the various parts of my device whereby the objects contemplated are attained, as hereinafter more fully set forth, pointed out in the claims and illustrated in the accompanying drawings, wherein the single figure is a view of a heater or warmer showing a plurality of warming units, one of which is shown partially in section.

Referring now in detail to the drawings, the figure shows two containers or cells 12. These cells 12 are the same in both instances and a description of one will suffice for both. The cell 12 in the preferred and simplest form of the invention consists in a standard jar or globe. The present illustration shows such cells 12 made of glass, and accordingly ordinary canning jars may be used if desired.

The upper end of the cell 12 is provided with a reduced cylindrical portion 14 having the threads 16 formed thereon and terminating in an opening 18.

A cap or closure member indicated generally at 20 closes the opening 18 of the cell 12. The cap 20 is provided with a threaded flange 22 for threading onto the threads 16. The top part or closing element of the cap 20 as shown in the present instance may consist of an in-turned flange 24 fitting over a plate or disc 26. Plate 26 rests on the marginal edge of the opening 18.

2

The plate or disc 26 is preferably of a material which is heat resistant and possesses some degree of resiliency for retaining the cap in tight engagement on the cell 12, and preventing it from turning off.

In the center of the plate 26 is a socket opening 28 in which is inserted an electric socket 30. The socket 30 may be any standard socket and includes a pair of rings 32 which engage opposite sides of the plate 26 at the marginal edge of the central socket opening 28. The lower ring is turned up tight against the plate 26 and thereby holds the socket 30 in place in the plate 26.

An electric cord 34 leads from the socket to a common lead 36.

Formed in the plate 26 are a plurality of air holes 38 for the proper circulation of air through the cell.

The plate 26 in the preferred form is of rigid material for supporting the socket 30 in rigid position. An electric light bulb 40 is inserted in the socket 30 and thereby positioned in the interior of the cell 12. Interposed in one of the electric cords 34 is a switch 42 for controlling the respective cell 12. In the common lead 36 is another switch 44 for controlling both of the heating cells.

A cord 46 is secured between the socket 30 and the electric cord 34 adjacent the socket, for taking the load of the cell off of the socket and sustaining it by the electric cord 34.

The device is particularly adapted as a bed-warmer. All of the heat generated by the device is confined in the bed and the device thereby becomes efficient. Control may be had by the electric switch and control may be regulated to a finer degree by burning on and off only one of the heating elements instead of both, if so desired.

While I have herein shown and described a preferred embodiment of my invention, manifestly it is susceptible of modification and rearrangement of the parts without departing from the spirit and scope thereof. I do not, therefore, wish to be understood as limiting my invention to the precise form herein disclosed, except as I may be so limited by the appended claims.

I claim as my invention:

1. In a device of the class described, a cell having an opening therein, the margin of said opening having threads formed on the outer surface thereof, a closure member removably threaded on said threads, said closure member having an electric socket opening formed therein, an electric socket removably secured in said socket opening, clamp means secured to said socket and engaging

said closure member on opposite sides of the latter, said socket being disposed for supporting an electric bulb in the interior of said cell.

2. In a device of the class described, a rigid wall cell having a generally cylindrical opening therein, the margin of said opening having threads formed on the outer surface thereof, a disc of resilient friction material covering said opening, said disc having sufficient rigidity to sustain substantially its shape, a threaded ring threaded on 10 said opening, said ring having an inturned portion engaging said disc and retaining the latter in place on the opening, a socket opening in said disc, an electric socket removably secured in said socket opening, annular clamp means secured to 15 said socket in surrounding relation thereto and engaging said disc on opposite sides of the latter,

said socket being disposed for supporting an electric bulb in the interior of the cell, said disc having a plurality of openings therein in addition to said socket opening.

JOHN S. LATTA, SR.
